[57] CLAIM

The ornamental design for a control head for a radio, as shown and described.

DESCRIPTION

FIG. 1 is a top, front and right side perspective view of a control head for a radio showing my new design;

FIG. 2 is top plan view thereof;

FIG. 3 is a front elevational view thereof;

FIG. 4 is a right side elevational view thereof;

FIG. 5 is a left side elevational view thereof;

FIG. 6 is a bottom plan view thereof;

FIG. 7 is a rear elevational view thereof;

FIG. 8 is a front elevational view of a second embodiment of the control head for a radio illustrated in FIG. 1;

FIG. 9 is a front elevational view of a third embodiment of the control head for a radio illustrated in FIG. 1;

FIG. 10 is a front elevational view of a fourth embodiment of the control head for a radio illustrated in FIG. 1;

FIG. 11 is a front elevational view of a fifth embodiment of the control head for a radio illustrated in FIG. 1;

FIG. 12 is a front elevational view of a sixth embodiment of the control head for a radio illustrated in FIG. 1; and

FIG. 13 is a front elevational view of a seventh embodiment of the control head for a radio illustrated in FIG. 1;

The top, bottom, rear and sides of the embodiments disclosed in FIGS. 7 through 12 are identical to the corresponding views of the embodiment disclosed in FIG. 1.

The broken line showing of the electrical connection in FIGS. 4, 5 and 7 is for illustrative purposes only and forms no part of the claimed design.

FIG. 1

FIG. 2**FIG. 3****FIG. 4****FIG. 5****FIG. 6****FIG. 7****FIG. 8**

FIG. 9

FIG. 10

FIG. 11

FIG. 12

FIG. 13
